ABSTRACT: Longitudinal support ribs on the unitary manifold divide the incoming volume of water (during backwash operation) into a plurality of equal and independent water columns which in turn are exhausted into similarly numbered segmental chambers of the said several filter grids. The manifold unit comprises a segmentally divided outlet area and a cross-sectionally smaller drive-adapter end over which the grid and grid spacer elements may be axially slid for interlocking with an elongate ribbed body of the manifold units.

UNITARY MANIFOLD AND INDEPENDENT
INTERLOCKING GRID CONSTRUCTION FOR WATER
FILTRATION SYSTEMS

This invention relates to water filtration systems such as are used in swimming pools and the like, and which with periodic supply of diatomaceous earth, employs a water manifold having mounted substantially concentric thereon, a plurality of spaced grid filter elements covered at faces thereof with skins of water-porous synthetic material. The general type of manifold and spaced filter grid construction to which this invention relates includes with a general reverse-current, backwash filter-cleansing operation, a torque-applying medium such as a crank for revolving the manifold and the filter grids mounted thereon during the backwash operation.

Prior art manifold and grid structures of the general type providing for rotation during backwash cleansing, fall generally into two classes known as "tube-type" and "rod-type" respectively. In both types no provision is made for any interlocking relationship of the grid elements or spacer elements, individually to the manifold proper.

In the tube type of the prior art the hollow manifold tube has communication radially at numerous points with the grid structure, and the grids and intervening spacer elements are clamped together longitudinally of the tube by forward and rear retaining clamping rings or the like. Distribution of the incoming water to the grid elements is somewhat haphazard and is not controlled by any divisions or means for setting up separate and distinct columns during travel through the manifold, as in our improved structure.

In the rod type of manifold, spacers and discs, an outlet adapter of annular form (separate from the manifold) is provided, which has a spider or central element screw threaded or otherwise secured to the axial rod and a pinned retainer plate clamps the grid and spacer elements against the inner annular edge of the separate outlet adapter to inefficiently interconnect the parts without any provision of positive interlocking of grid elements or spacer elements with the overall manifold structure. The structure elements themselves, constitute the main portions of the manifold. Here again there is no provision in the manifold for dividing water flow either in the normal incoming water flow or in a backwash cleansing operation to provide for even distribution by columns of water.

In both types of the prior art manifold and grid structures the clamping force applied to the clamped axial ring portions of the grid elements is severe, and with wear fracture of said elements or injury or loosening of the grids often occurs.

My invention has, for a main object the provision of a plurality of longitudinal support ribs guiding the incoming volume of water into a plurality of equal and independent columns which in turn are exhausted into the segmental chambers of the element support grids. This not only provides for a predetermined and equally divided passage of water when the water is first exhausted into the filtration chamber, but furthermore in the backwash cleaning operation assures a more thorough cleansing of the porous filter elements on the grids.

Another important object is to provide, in a single unitary manifold device capable of being very economically manufactured, an outlet adapter or area, a rib grid support and positive locking area, and a rotational crank adapter.

A further object is to overcome the previously noted objections to the prior art structures wherein a single manifold unit is provided to replace and improve, and better prior art structures, and where grids as well as the spacers are maintained in a locked position to evenly distribute rotational force to the grid and spacer elements.

The foregoing and other objects and advantages of my invention will more fully appear from the following description made in connection with the accompanying drawings wherein like reference characters refer to similar parts throughout the several views, and in which:

FIG. 1 is a top plan view of a preferred embodiment of my improved unitary manifold with central portions only of the spaced filter grids being shown in operative position, one of

the grid elements and a spacer element being applied to the manifold with the remaining portion of the manifold exposed;

FIG. 2 is an end elevation of the manifold with grids and spacers removed, and showing the outlet adapter;

FIG. 3 is a fragmentary cross section taken on the line 3-3 of FIG. 2;

FIG. 4 is a cross section taken on the line 4-4 of FIG. 1, showing interlocking and partition-forming ribs;

FIG. 5 is an end elevation of the manifold showing the crank adapter and retaining ring end;

FIG. 6 is a fragmentary front elevation of one of the grid elements detached with most of the covering filter sheet broken away;

FIG. 7 is a vertical cross section taken on the line 7-7 of FIG. 6 showing the grid structure;

FIG. 8 is a diagrammatical view mostly in vertical section and on a reduced scale of my improved combinative structure assembles with the crank attached to the adapter at the forward end of the manifold and with the device ready for backwash cleansing of the filter and grid elements; and

FIG. 9 is an end elevation of one of the spacer elements detached.

Referring now in detail to the drawings, I provide a unitary, preferably single unit manifold indicated as an entirety by the letter M, having an elongate body composed of a plurality of preferably integrally formed ribs 10 extending through the greater part of the overall manifold length and extending in cross-sectional shape radially from a common, longitudinal center line. In the embodiment illustrated, four of said ribs 10 are employed, being of equal width and straight in length to form elongate divider partitions for water passing generally axially through the manifold and the filter grids mounted thereon.

Manifold M has an outlet adapter and area 11 constituting the front end portion thereof, having a cylindrical periphery 11a provided with an external circular groove 11b and a tapered extremity 11c. An upstanding annular grid-abutment shoulder 11d is provided forwardly of cylindrical periphery 11a.

As shown in FIGS. 2 and 3, narrowed rib extensions 10a extend internally through the outlet dividing the interior thereof into four equal segmental passages 12. The rib extensions 10a do not extend fully to the annular extremity of outlet 11 as will be clear from inspection of FIG. 3.

At the opposite and rear end portion of manifold M, a combination adapter 13 is provided for receiving and securing respectively, an annular grid retainer R and a crank handle C, having a square internal socket end C-1 for interlocking engagement with the outer squared end portion 13a of the adapter 13. As shown, the inner end portion 13b is externally threaded to engage and lock with the internal threads of annular grid retainer R. A circular shoulder 13c of somewhat larger diameter than threaded portion 13b serves as a reinforcement for the elongate, segmental channels defined by the four ribs 10. It will be noted that the diameter of shoulder 13c is considerably less than the combined widths of two aligned integral ribs 10.

A plurality of large diameter, foraminous grid elements designated as entirites by the letter G are provided, having continuous circular peripheral edges G-1 and thickened and concentric interior mounting collars G-2 (see FIGS. 6 and 7). Collars G-2, at their inner circular edges are notched to form rib-interlocking elements G-3 equally spaced apart and corresponding in number to the four manifold ribs 10.

The two faces of the foraminous grids G are covered with filter sheets F-S of conventional type, water-porous fabric. Sheets F-S are centrally apertured to surround the mounting collar G-2 of the grid elements.

In assembling the components of my manifold and grid structure the grid elements G and spacer elements S are alternately and successively axially slid over the crank adapter 13 of the integral manifold, the open grid mounting collar portions G-2 being properly turned to cause interlocking engage-

ment between the interlocking notches G-3 and the outer edges of the ribs 10. Likewise, the spacer elements S are axially disposed of the crank adapter 13 with the interlocking notches. S-1 being properly aligned for interlocking with the outer portions of the ribs 10.

The first grid element G applied is slid to a position in abutment against the abutment shoulder 11d of the outlet adapter. The adjacent spacer element S is then applied and abutted against the central mounting-collar portion G-2 of the first grid. Successive grid and spacer elements are then applied, it being of course understood that in most instances to economize for maximal filtration, a grid element is disposed last upon the manifold, with its outer surface of its mounting collar being position for engagement by the opposing face of the retaining threaded member R. Crank handle C is usually rigidly connected with the squared end 13a of the adapter by suitable means such as a set screw transversely carried by square socket C-1.

From the foregoing description it will be seen that with my structure a single unit manifold is provided, capable of being economically manufactured by injection molding or casting from a variety of plastic, alloy and composition material. The use of polyvinylchloride for injection molding of the entire manifold has been proven highly successful. Of course the manifold which includes the elongated, multirib section, the outlet adapter section, and the combination retainer ring and crank adapter section may be constructed from the harder aluminum alloys, other metals, and including stainless steel.

After outward flow of the water into the filtration chamber, a very efficient backwash cleansing operation may be obtained by manually or power-rotating crank C which in turn rotates the entire manifold with its independently interconnected grids and spacers. Torque power is uniformly applied to all grids and spacers by the interlocking relation of the manifold ribs with the engaged notches G-3 and the notches S-1 of the spacer elements.

It will be seen that in travel of the water through manifold in either direction, the water is divided by ribs 10 (in the form shown) into four equal columns, passing in turn through the four segmental passages which are defined between each pair of grid elements G.

My improved structure may be manufactured more economically than manifold grid and spacer structures now in extensive use and will assure a better distribution of the water to be filtered, and also water for backwash purposes, than any of the prior art structures known to applicant.

No clamping pressure is utilized to interconnect grids, spacers and manifold, as in the structures of the prior art.

It will of course be understood that various changes may be made in the details and substitution of equivalencies in the parts provided they are covered in the appended or amended claims of this application.

I claim:

1. In a water filtration system employing in a filtration chamber, a plurality of spaced, filter grid discs, annular spacer elements between said discs, and manifold means for coaxially mounting said grids and spacer elements,

5 those improvements which have in combination; a unitary manifold member having an outlet area at one of its end portions and having a cross-sectionally smaller crank adapter element at its opposite end portions; said manifold member through most of its length, comprising a plurality of multi-functional joined longitudinal ribs extending in cross section substantially radially from a common longitudinal center line, and extending longitudinally at least partly through said outlet area to divide the interior thereof into a plurality of independent water passages;

said grid discs having concentric, axial apertures of somewhat smaller diameter than a circle circumscribed about the peripheries of said ribs and being internally notched at the edges defining said apertures at spaced points corresponding to the number of said ribs, for slidably receiving the outer portions of said ribs when said discs are axially applied over said adapter end portion of said manifold member to interlock said discs in spaced reinforcing relation upon said ribs, and means for mounting said annular spacer elements between said discs; and said ribs, when flow of water is set up through said outlet passage, dividing said flow into a plurality of independent columns which in turn exhaust into segmental chambers of said grid discs.

20 2. The structure set forth and defined in claim 1 wherein a tubular manifold member including said outlet area, said crank adapter element and said ribs, is integrally formed from substantially rigid material.

25 3. The structure set forth and defined in claim 1 further characterized by, said outlet area having inwardly disposed of its terminal portion, an outstanding abutment shoulder of somewhat larger diameter than the axial apertures of said disc for abutment with said disc about said apertures, and an annular retaining element fixedly engageable with said crank adapter portion and positioned for substantial abutment against a disc at the opposite end of said manifold.

30 4. The structure defined in claim 1 wherein said annular spacer elements are internally notched similarly to said grid discs for nonrotative, interlocking with the outer portions of said ribs.

35 5. The structure set forth and defined in claim 1 further characterized by at least said crank adapter, said outlet area and said manifold being integrally formed, and said annular spacer elements having axial apertures of somewhat smaller diameter than a circle circumscribed about the peripheries of said ribs and being internally notched at the apertured edge at spaced points corresponding to the number of said ribs.
